UNITED STATES PATENT OFFICE

2,522,103

UNIVERSAL LAMP HOLDER AND SAFETY SWITCH

Earl D. Drake, Detroit, Mich., assignor to
Broker Engineering Co., Detroit, Mich.

Application April 5, 1946, Serial No. 659,698

2 Claims. (Cl. 200—51.09)

1

This invention generally relates to fluorescent lamp lighting fixtures and particularly pertains to a high voltage lamp holder that is equipped with a universally adaptable lamp electrode receiver and a primary low power lead switch that is operated by inserting or removing the lamp from the holder.

The environment of the invention are the low powered primary leads from the power source to a transformer, the high powered secondary leads from the transformer to the lamp holders, and the lamp holders which house the universally adaptable lamp electrode receiver and the low power lead switch which is disposed in the primary circuit between the power source and the transformer.

Pertinent to the following objects of this invention, as fluorescent lighting necessitates the use of high voltage to operate same, the danger of electrocution, electric shock or burn to persons installing, using or repairing same is always imminent even if the persons are expert and the danger is many times multiplied by the inexpert and the uninformed who use or attempt replacements and repairs on a high power system with the danger potential at its highest when a lamp is removed from a live socket and that socket is left exposed.

It is, therefore, an object of the invention to provide a switch or a series of switches in the primary leads between the power source and the transformer which are operable by inserting or removing the lamp in or from the socket of the lamp holder with the switch being placed in the "on" position when the lamp is inserted in the holders and in the "off" position when the lamp is removed from the holders. This action powers the socket when the lamp is in the holder and cuts off power when the lamp is not in the holder thereby leaving the socket without power while in an exposed condition.

Another object is to supply a switch in the primary or low voltage leads of a high voltage lamp holder operable by inserting the item in or removing the item from the high voltage holder as a switch in the low voltage leads of a high voltage holder is not subject to the danger of flashing and arcing that a switch in the high voltage leads would be subject to in turning "on" or "off" the high voltage.

A further object is to provide a universally adaptable lamp electrode receiver which will receive the various types of lamps with their various types of electrodes the purpose of which is to allow the holder to receive and operate any

2

make of lamp of the cold cathode or single electrode type.

Other objects and advantages will be apparent from the following description and the attached drawings, in which:

Fig. 1 is an elevational view of the lamp holders in the invention, showing the primary and secondary wiring diagram;

Fig. 2 is a cross sectional view of one of the lamp holders in the invention showing the switch disposed therein and the electrode receiver cup; and

Fig. 3 is a like view to Fig. 2 of the mating lamp holder showing the electrode receiver cup therein.

Referring to Fig. 1, and relative to the primary wiring from power to the transformer, 110 volt neutral or grounded lead 10 is directly connected to transformer 11 while 110 volt positive or ungrounded lead 12 is indirectly connected to the transformer 11 via plunger type switches 14 and like switch 14—A housed in lamp holders 15 and like holder 15—A respectively, which switches are diagrammatically shown in this figure.

Again referring to Fig. 1, and now describing the secondary wiring from the transformer 11 to the lamp holders, 750 volt leads 16 and 17 are connected in line to the lamp holders 15 and 15—A while 750 volt common lead 19 is connected in series to mating lamp holders 20 and 20—A with the lamp 21 disposed in the secondary wiring by placing same in the holders 15 and 20 relative to the opposite ends of the lamp 21.

It can now be seen that the switch 14 in the holder 15 in which the lamp 21 is inserted, is in the closed or "on" position as diagrammatically shown, while the switch 14—A in the holder 15—A in which there is no lamp 21 inserted, is in the open or "off" position with the result that the transformer 11 is still disconnected from power leaving the exposed sockets 15 and 15—A unpowered or "dead." By inserting another lamp 21 between the exposed socket 15—A and mating socket 20—A, the open switch 14—A will be closed and power transmitted to the transformer 11 which will, in turn, power the lamps 21 in the fixture.

Pertinent to the structure of the lamp holders 15 and 20 and taking up the parts of each that are common to both, cylindrical body portion 22, Figs. 2 and 3, has slots 23 formed therein and extending longitudinally thereof, flange 24 housing apertures 25 formed integrally therewith, and bottom part 26 also formed integrally there-

with housing apertures 27 for receiving bus-bar fastening screws 28 with dished portion 29 formed in the bottom part 26. The apertures 25 are used to attach the holder 15 to a suitable fixture.

Relative to the parts particular to the holder 15, bus-bars 30 equipped with terminal screws 31 are positioned internally of the body portion 22 extending through the slots 23 and secured against the bottom part 26 by the bus-bar fastening screws 28, with gap 45 between the internally disposed ends of the bus-bars 30. Insulating washer 32 adjoins the bus-bars 30 with spring 33 disposed between the washer 32 and plunger 34 which carries plunger rod 35 and adjoins universally adaptable lamp electrode cup shaped receiver 36 which, in turn, adjoins stop collar 37 which is secured to the body portion 22 by collar fastening screws 38 which are of the self-tapping type and which prevent the stop collar from being forced out of the body portion 22 by the spring 33. The lead 16 or 17 is connected to the receiver 36 by pig-tail type connection 39 and the receiver 36 in conjunction with the collar 37 form a receiving socket for one end of a lamp 21.

Referring now to the parts particular to the lamp holder 20, bus-bar 40 is in like position to bus-bars 30 and carries like terminal screws 31 while brass spring 41, more strongly constructed than the spring 33, contacts the bus-bar 40 and extends to and contacts cup receiver 42 equipped with flange 43 with the cup receiver 42 abutting stop collar 44 which is secured by screws 38 the same as the stop collar 37 and the receiver 42 and the collar 44 form a receiving socket for the other end of a lamp 21.

Concerning the materials used in the fabricating of the various parts, the body portion 22 is made of non-electrical conducting material as well as the stop collars 37 and 44, the washer 32 and the plunger 34 while the bus-bars 30 and 40, the spring 41 and the cup receivers 36 and 42 are constructed of electrical conducting material.

Considering the lamp holders 15 and 15-A and 20 and 20-A, in relative positions as shown in Fig. 1, and pertinent to the wiring connections, lead 12 is broken and connected in series to the transformer 11 by running the lead 12 through the switches 14 and 14-A by attaching the lead 12 to the bus-bars 30 via the terminal screws 31 and the leads 16 and 17 are connected by the pig-tail connection 39 to the cup receivers 36 with the neutral lead 10 connected directly to the transformer 11 and the neutral lead 19 connected in series to the lamp holders 20 and 20-A via the terminal screws on the bus-bars 40 which lead through the spring 41 to the cup receivers 42. It is now seen that the cup receivers 36 and 42 are at end positions relative to the positive and neutral leads 16 or 17 and 19 and that the secondary circuit can now be closed by inserting a lamp 21 in the holders 15 and 20 which insertion is accomplished by putting one end of a lamp 21 into a holder 20 internally of the collar 44 and by forcing back the spring 41 via cup receiver 43 so that the other end of the lamp 21 can be inserted into the holder 15 internally of the collar 37 which action is allowed by the long travel of the spring 41, the lamp 21 is forced into the holder 15 by same as the spring 41 overcomes the spring 33 via the lamp 21, the cup receiver 36 and the plunger 34.

This action forces the plunger 34 to the left as seen in the drawings carrying the plunger rod 35 into contact with the bus-bars 39 and closing the gap 45 between them which puts the

switch 14 in the closed position. By inserting another lamp 21 in the holders 15-A and 20-A, the same action takes place and both switches 14 and 14-A in the lead 12 are then closed which allows power to be transmitted to the transformer 11 which feeds back the stepped up power via the secondary circuit and powers the lamps 21.

Conversely, by removing a lamp 21 from the fixture, the primary circuit is interrupted as a switch 14 opens due to the spring 33 forcing the plunger 34 to the right as seen in the figures which carries the plunger rod out of contact with the bus-bars 30 and opens the gap 45 between them thereby interrupting the circuit 12, cutting off power to the transformer 11, and leaving the exposed sockets 15 and 20 without power or "dead" so that a "live" socket is not left exposed which eliminates the greatest potentiality of anyone being injured or killed by the high electrical power used in the apparatus.

Relative to the receivers 36 and 42 which are identical except for the flange 43 on the receiver 42, apertures 46 are formed in each receiver adaptable to receive a long type lamp electrode, curved or cupped portion 47 on each receiver are adaptable to receive a button type lamp electrode, while the flat portions on each receiver are adapted to contact the rim type lamp electrode which enables the receivers 36 and 42 to be universally adaptable to receive and contact the various type of electrodes on the lamps of different manufacturers.

The lamps 21 and holders 15 and 20 can be disposed singly or in pairs or sets of more than two and can be arranged in batteries of multiple sets and the sets may or may not be balanced, which is, to say, synchronized to eliminate the stroboscopic effect of the lamp pulsations.

Various adaptations, substitutions, additions and omissions can be made relative to the invention herein described without departing from the spirit thereof as the invention is limited only by the scope of the appended claims.

45. I claim:

1. In combination with a tubular lamp having an endwise projecting conductor pin, a lighting tube socket including a tubular body portion, spaced bus-bars at one end of said body portion, a reciprocating plunger in said body portion, a plunger rod carried by said plunger for bridging said bus-bars when positioned at one end of said body portion, a spring normally urging said plunger rod from engagement with said bus-bars, a cup-shaped apertured receiver in the end of said body portion opposite to the bus-bar end and being reciprocative in the body portion with said plunger, said receiver adapted to receive the conductor pin of said lamp through its aperture, an electrical contact member at the bus-bar side of said receiver for contacting the conductor pin of said lamp, and stop members at the opposite ends of tubular body portion.

2. In combination with a tubular lamp having an endwise projecting conductor pin, a lighting tube socket comprising a tubular body portion, an apertured receiver therein, a collar carried by said body portion at one side of said receiver for receiving an end of said tubular lamp, an electrical contact member on the opposite side of said receiver to said collar for contacting the conductor pin of the tubular lamp, spaced bus-bars at the opposite end of said body portion, a reciprocating plunger in said body portion be-

tween said bus-bars and said electrical contact member, a plunger rod carried by said plunger for bridging said bus-bars when positioned at one end of said body portion, and a spring between said bus-bars and said plunger normally urging said plunger rod from engagement with said bus-bars, whereby the flow of current between said bus-bars establishes a flow of current through said electrical contact member.
